150,365

DESIGN FOR A COFFEE TABLE OR SIMILAR ARTICLE

Dan R. Johnson, Los Angeles, Calif.

Application September 3, 1946, Serial No. 133,025

Term of patent 3½ years

(Cl. D33—14)

To all whom it may concern:

Be it known that I, Dan R. Johnson, a citizen of the United States, residing at 6215 Franklin Street, Los Angeles, in the county of Los Angeles and State of California, have invented a new, original, and ornamental Design for a Coffee Table or Similar Article, of which the following is a specification, reference being had to the accompanying drawings, forming a part thereof.

Fig. 1 is a perspective view of a coffee table or similar article showing my new design;

Fig. 2 is an oblique view thereof;

Fig. 3 is a front plan view thereof;

Fig. 4 is an end plan view thereof;

Fig. 5 is a top plan view.

I claim:

The ornamental design for a coffee table or similar article, substantially as shown.

DAN R. JOHNSON.
